UNITED STATES PATENT OFFICE.

FRED MELL GARNETT, OF SAVANNAH, GEORGIA.

TOPOGRAPHER'S RULE.

Application filed February 6, 1925. Serial No. 7,383.

To all whom it may concern:

Be it known that I, FRED M. GARNETT, a citizen of the United States, residing at Savannah, in the county of Chatham and State of Georgia, have invented a new and useful Topographer's Rule, of which the following is a specification.

This invention aims to provide a simple means whereby a topographer, working anywhere, but more especially in the field, may draw conventional signs rapidly, without shifting to any great extent, the scale whereby the distance from the transit to the object to be platted is laid off.

It is within the province of the disclosure to improve generally and to enhance the utility of devices of that sort to which the invention appertains.

Although a preferred form of the invention has been shown, it will be understood that an instrument maker, working within the scope of what is claimed, may make such changes as his skill may suggest, without departing from the spirit of the invention.

In the accompanying drawings:—Figure 1 shows in plan a device constructed in accordance with the invention; Figure 2 is a cross section on the line 2—2 of Figure 1; Figure 3 is a fragmental longitudinal section; Figures 4, 5 and 6 are views illustrating some of the conventional signs which may be drawn by means of the instrument forming the subject matter of this application.

In carrying out the invention, there is provided a strip 1, made of any suitable material and provided along one edge with a scale 2, the strip 1 being beveled, if desired, as shown at 3, to that edge whereon the scale 2 is located. The strip 1 is provided at one end with a hole 4, whereby the strip may be suspended when not in use. The opening 4 is for the purpose of attaching the rule to the topographer's coat or vest, whilst the rule is being used in the field. The rule, therefore, is not likely to be lost, as would be the case if it were kept in the pocket or carried in a note book. By suspending the rule with a string, it will be available at all times for instant use, and will not have to be put into the pocket.

The strip 1 is provided with a plurality of openings, so shaped that when a pencil is moved about the edges of the openings, conventional signs will be formed. Having this consideration in mind, the strip 1 has a

rectangular opening 5, adapted to be used in the drawing of the sign representing a railroad station or pavilion. Rectangular openings 6, 7 and 8, of different sizes, are provided, and the same are used for drawing signs representing houses. An irregular rectangular opening 9 is used for making the sign of a house of corresponding shape. The triangular opening 10 shown in Figure 1 is useful for many purposes, for instance, for indicating a triangulation point. The strip has a circular opening 11 surrounded by a concentric slot 12. These elements sometimes are used in the representation of a hub or transit point. The numeral 14 marks a rectangular opening provided at its corners with diverging restricted slots 15. This opening, or a similar opening 17, are resorted to in the drawing of the sign 16 for a bridge. A circular opening 18 having diametrically opposite slotted extensions 19 forms the sign for a telegraph pole. An arrow-shaped opening 20 produces the sign 21, indicating direction. The arcuate opening 31 is employed for indicating curves of any kind, for instance in a highway. Arcuate slots 22 and 23, on different radii, have a utility which will be understood readily by those skilled in the art.

The strip 1 is supplied with parallel slots 24 adapted for making the sign 25 indicating, for instance, a highway. A similar slot 26 is used in the drawing of a single straight line. Across the slots 24 and 26 extend bridges 27, the maximum height of each bridge being less than the depth of the slot, as clearly indicated at 30 in Figure 3. The upper surfaces of the bridges 27 are curved, as indicated at 28, preferably upon a parabola or cycloid, so as to present thinned edges 30. It is clear that when the pencil, shown diagrammatically in Figure 3, is drawn along one of the slots 24, or along the slot 26, the pencil will ride up easily upon the bridges 27, owing to the fact that the bridges have thinned edges 30, spaces being formed between the dashes in the sign 25 shown in Figure 4. Because the maximum height of each bridge 27 is less than the depth of the slot, the pencil cannot jump out of the slot, as the pencil is drawn along.

The device is made of a transparent substance. The transparency of the rule enables the topographer to sketch in the fig-

ures in their relative positions, since the center line of the survey is shown in the note book in red, all figures and approximate distances being referred to this line. Since it is possible for the topographer to see through the rule, the conventional signs may be oriented properly with respect to the center line of the survey. It is suggested that the rule may be made out of 10 xylonite or celluloid.

Having thus described the invention, what is claimed is:—

A topographer's rule supplied with a slit, the rule being provided with spaced bridges

extended across the slit, the height of the 15 bridges being appreciably less than one-half the thickness of the rule, the bridges having oppositely disposed thinned edges which coincide with the lower surface of the rule, the upper surface of each bridge being 20 continuously convexed from one of said thinned edges to the other, the slit being narrow enough to constrain a stylus to right-line movement.

In testimony that I claim the foregoing as 25 my own, I have hereto affixed my signature.

FRED MELL GARNETT.
